UNITED STATES PATENT OFFICE

ARCHIE LIBERTY, OF AMASA, MICHIGAN

WATER LIFT

Application filed May 6, 1929. Serial No. 360,761.

This invention relates to a water lift and has for its primary object to provide, in a manner as hereinafter set forth, a device of such character including as a part thereof, 5 means for creating an eddy within a well above the level of the water therein, whereby water may be raised from the well to a tank located exteriorly thereof.

With the foregoing and other objects in view, the invention consists of the novel construction, combination and arrangement of parts as hereinafter more particularly described, and as illustrated in the accompanying drawings wherein is shown an embodiment of the invention, but it is to be understood that such description and drawings are to be taken as illustrative and that the invention is intended to be limited only by the scope of the claims hereunto appended.

In the accompanying drawings in which like numerals are employed to designate like parts throughout the same:

Figure 1 is a sectional elevation of a water lift constructed in accordance with this invention.

Figure 2 is a section taken on line 2—2 of Figure 1.

Referring to the drawings in detail, the 20 numeral 1 indicates the wall of a well within which is suspended a casing consisting of an upper section 2 and a lower section 3. The sections 2 and 3 are connected together by means of a dividing wall 4 which is provided with an opening 5 extending vertically therethrough to establish communication between the interiors of the sections. The wall of the opening 5 is flared at its lower end as indicated at 6. The lower section 3 is adapted 35 to be extended below the level of the water in the well and is provided adjacent its lower end with a plurality of openings 7 through which water may pass from the well to the interior of the lower section. The upper section 2 is of less diameter than the lower section 3 and is provided at its upper end with a discharge pipe 8, which empties into a tank 9 suitably disposed with respect to the well.

50 Mounted within the lower section 3 is a

hollow cylinder 10, the diameter of which is substantially equal to the maximum diameter of the opening 5 and the upper end of which is disposed in spaced relation to the lower end of the opening 5. The lower end 55 of the cylinder 10 is provided with a pair of spaced bearings 11 and 12, within which is rotatably mounted the shaft 13 of a cylindrical propeller 14. Extending around the cylinder 14 in spiral formation is a plurality of ribs 15 for a purpose to be hereinafter disclosed.

Adapted for extension into the tank 9 is a suction pipe 15', which is operatively connected with a pump 16. Extending from 65 the pump 16 is a main supply pipe 17, through which the water from the tank 9 may be transmitted to any point desired. Connected with the supply pipe 17 is a pressure pipe 18 which extends through the head 70 19 of the section 2 and the lower end of which opens into the cylinder 10, adjacent the bottom of the latter.

In the operation of my water lift, an initial supply of water is placed in the tank 75 9 which may be drawn therefrom through the suction pipe 15' by the action of the pump 16. The water drawn from the tank 9 is passed into the supply pipe 17 and a portion thereof is forced under pressure through the 80 pipe 18 into the lower end of the cylinder 10. When the water from the pressure pipe comes in contact with the ribs 15 on the rotatable cylinder 14, a rotary motion is imparted to the cylinder, and the water is forcibly discharged from the upper end of the rotatable cylinder 14 and through the opening 5 with a whirling motion which creates an eddy between the walls of the cylinder 10 and the lower section 3. The eddy thus created lifts 85 the water within the lower section 3 through the opening 5 and upper section 2 from where it is discharged through the pipe 8 into the tank 9 with the water which entered the section 2 under pressure.

90 It is thought that the many advantages of a water lift in accordance with this invention will be readily apparent, and although the preferred embodiment of the invention is as illustrated and described, yet it is to be un- 100

derstood that various changes in the details of construction may be resorted to, so long as such changes fall within the scope of the invention as defined in the appended claims.

What I claim is:

- 5 1. A water lift comprising, a casing for extension into a well and consisting of an upper and lower section, the lower section having means to establish communication between the interior thereof and the well, a dividing wall connecting the sections and formed with an opening to establish communication therebetween, a hollow cylinder within the lower section, a propeller rotatably mounted within the hollow cylinder, a tank exteriorly of the well for containing an initial supply of water, means for pumping water from the tank, and a pressure pipe connected with such means for transmitting a portion of the water pumped from the tank under pressure to the hollow cylinder for operating the propeller to create an eddy within the lower section to lift water from the well.
- 10 2. A water lift comprising, a casing for extension into a well and consisting of an upper and lower section, the lower section having means to establish communication between the interior thereof and the well, a dividing wall connecting the sections and formed with an opening to establish communication therebetween, a hollow cylinder within the lower section, a propeller rotatably mounted within the hollow cylinder, a tank exteriorly of the well for containing an initial supply of water, means for pumping water from the tank, and a pressure pipe connected with such means for transmitting a portion of the water pumped from the tank under pressure to the hollow cylinder for operating the propeller to create an eddy within the lower section to lift water from the well.
- 15 3. A water lift comprising, a casing for extension into a well and consisting of an upper and lower section, the lower section having means to establish communication between the interior thereof and the well, a dividing wall connecting the sections and formed with an opening to establish communication therebetween, a hollow cylinder within the lower section, a propeller rotatably mounted within the hollow cylinder, a tank exteriorly of the well for containing an initial supply of water, means for pumping water from the tank, and a pressure pipe connected with such means for transmitting a portion of the water pumped from the tank under pressure to the hollow cylinder for operating the propeller to create an eddy within the lower section to lift water from the well, said opening through the dividing wall being flared at its lower end, said hollow cylinder having a diameter substantially equal to the maximum diameter of said opening and having its upper end disposed in spaced relation to the lower end of said opening.

In testimony whereof, I affix my signature hereto.

50 ARCHIE LIBERTY.
